CONTAINER

Benjamin M. Williams, St. Louis, Mo., assignor to
 Gaylord Container Corporation, St. Louis, Mo.,
 a corporation of Maryland

Application December 20, 1937, Serial No. 180,688

7 Claims. (Cl. 229—44)

My invention relates to a container, particularly to a container made of fiber-board or other bendable material and especially adapted for use in shipping bottled products.

The principal object of the invention is a container which utilizes comparatively light material, but which is so constructed as to have the necessary strength and rigidity. Another object is to protect the upper edges of the end walls of the container. Other objects and advantages will appear hereinafter.

The invention consists principally in the construction of the end wall and cover members whereby the desired strength and rigidity are obtained. The invention further consists in the container and in the parts and combinations and arrangements of parts hereinafter described and claimed. In the accompanying drawings, wherein like reference characters indicate like parts,

Fig. 1 is a plan view of the body blank for a container embodying my invention;

Fig. 2 is a plan view of an end blank;

Fig. 3 is an end elevation of the assembled container, with the cover portions closed;

Fig. 4 is a top plan view, a portion of the cover members being broken away;

Fig. 5 is a cross-sectional view on the line 5—5 in Fig. 4;

Fig. 6 is a detail sectional view through the abutting portions of the cover member flanges looking towards the inner face of an end wall;

Fig. 7 is a sectional view on the line 7—7 in Fig. 6;

Fig. 8 is a partial end elevation of the inner face of an end wall;

Fig. 9 is a sectional view on the line 9—9 in Fig. 8;

Fig. 10 is a top plan view of the middle portion of an end wall;

Fig. 11 is a partial end elevation of the outer face of an end wall; and

Fig. 12 is a view similar to Fig. 7 showing a modification.

In Fig. 1 is illustrated a body blank A which is preferably made of fiber-board or the like and is divided up into a bottom panel 1, two side panels 2 and two cover panels 3, one at each end of the blank and each covering half of the top of the container. The division or joint between the bottom panel 1 and each side panel 2 is formed by score lines 4 which facilitate the folding up of the side panels 2, and the division or joint between each side panel 2 and its cover panel 3 is formed by similar score lines 5.

At each end of the bottom panel 1 is a flap 6

which is marked off by a score line 7. The end edges 8 of these flaps 6 are continuations of the score lines 4.

At each end of each side panel 2 is a flap 9 of the same width as the bottom panel flaps 6 and marked off from its side panels by a score line 10. The edge 11 of each of said flaps adjacent to a bottom panel flap 6 is cut away along a line extending angularly from the corner of the body panel and thence parallel with the body panel score lines, so that these flaps 10 are of reduced length to facilitate setting up the box. The other edge 12 of each of said flaps 9 is a continuation of a score line 5.

Each cover panel 3 has a score line 13 extending parallel to the score lines 4 and 5, marking the edge of a flange 14 and with a second parallel score line 15 marking off a flange lining strip 16, as will be further described in connection with the set-up box.

The cover panels 3 are provided with end flaps 17 of the same width as the flaps 6 and 9, the edge of each flap 17 adjacent to a side panel flap 9 being cut away similarly to the edge 11 of the side panel flaps 9. At the other end edge, each cover panel flap 17 is provided with a tongue 18 which is marked off by a score line 19 in continuation of the score line 13 and which extends the width of the cover panel flange 14 and flange lining strip 16. The edges 20 of the cover panel flange 14 and lining strip 16 are cut away similarly to the edges 11 of the side panel flaps 9.

Each end blank B comprises a body or end wall portion 21 of the same width as the bottom panel 1 and of the same height as the side panels 2, together with a flap 22 adapted to be bent inwardly and downwardly from the upper edge of the end wall in the finished box. The end wall proper 21 and the end wall flap 22 are divided by a wide or double score line 23, constituting a hinge connection between the end wall and its flap, as hereinafter described.

Each end wall 21 is provided with a horizontally disposed hand hole 24, the strip 25 removed from said hole being preferably utilized in strengthening the end wall as is hereinafter described.

The body portion 21 of each end blank is provided with a vertically disposed slot 26 in its upper edge, the bottom of said slot 26 being spaced from the top of the hand hole 24 by an amount equal to the width of the strip 25 removed in making the hand hole. The hinge portion 23 is provided with a slot 27 in continuation of said slot 26 which flares from the end of said slot 26.

26 to about the middle of the hinge portion 23 and then extends with its walls parallel to the walls of said main slot. A slot 28 in the end wall flap 22 is a continuation of the wide portion of said slot 27, the depth of said slot 28 being somewhat greater than the depth of the slot 26 in the end proper 21.

In the assembled box, the lower edges of the end walls 21 rest on the ends of the bottom panel 1 and against the ends of the inner faces of the side panels 2, the bottom panel flap 6 and the side panel flaps 9 being folded over against the end walls and secured thereto as by staples 29. The strips 25 are placed against the inner faces 15 of the end walls 21 with their lower edges flush with the upper edges of the hand holes 24 and with their upper edges flush with the bottoms of the end wall slots 26. The end wall flaps 22 are bent inwardly and downwardly against the end wall 21 and secured thereto as by staples 30, one staple passing through each end wall 21, strip 25 and end wall flap 22. The end wall flap 22 may extend to about the mid-line of the hand hole 24, in which case the lower edge of said flap 25 is provided with a recess 31 to align with the upper portion of the hand hole.

The cover panel end flaps 17 and flanges 14 are turned downwardly, the tongues 18 of the flaps 17 being bent against the inner faces of 30 the cover flanges 14. The flange lining strips 16 are then rebent upwardly and secured to the flanges 14, as by staples 32, some staples extending also through the tongues 18.

It will be noted that the cover panel flanges 14 and lining strips 16 are shorter than the distance between the end walls proper 21, but slightly longer than the distance between the inturned end wall flaps 22 and that the scored portion 15 which is bent over the tongues 18 projects below the level of the tongues. Thus, the tongues only 40 extend into the narrow slots 26 of the end walls proper and the end portions of the flanges 14 and flange lining strips 16 extend into the wider slots 28 of the end wall flaps 22, the increased depth of said slots of said end wall flaps accommodating 45 the depending end portions 33 of the cover flanges 14 and lining strips 16 and said depending portions 33 abutting against the strips 25, or against the end walls 21, if said strips be omitted as shown in Fig. 12.

50 The wide or double score line 23 of the end wall 21 provides a wide ledge or seat for the cover panels 3.

The above described container has important 55 advantages. The construction of the end walls and cover panels permits an interlocking and bracing arrangement that greatly increases the strength and rigidity of the box. The upper edges of the end walls are free from raw edges 60 which would deteriorate due to wear and moisture.

Obviously, numerous changes may be made 65 without departing from the invention and I do not wish to be limited to the precise construction shown.

65 What I claim is:

1. An end wall blank for a container of the kind described comprising a body portion having a slot in its upper edge, a marginal flap extending along said upper edge and a wide scored portion between said body and said flap, said scored portion and said strip having a slot flaring from the end of said first slot for some distance into said scored portion and then extending with its edges parallel to those of said first slot.

2. An end wall blank for a container of the kind described comprising a body portion having a slot in its upper edge, a marginal flap extending along said upper edge and a wide scored portion between said body and said flap, said scored portion and said strip having a slot flaring from the end of said first slot for some distance into said scored portion and then extending with its edges parallel to those of said first slot, the depth of the portion of said slot in said flap being greater than the depth of said slot in said body portion.

3. A container comprising side and end walls, said end walls having inturned upper marginal flaps, said end walls having slots in their upper edges and said inturned flaps having slots in line with said end wall slots but wider and deeper, cover panels hinged to said side walls, side and end flanges on said cover panels, and tongues carried by said end flanges and secured against the inner faces of said side flanges, said side flanges extending beyond said inturned flaps of said end walls but stopping short of said end walls, said tongues extending through said slots and the edges of said side flanges extending below the bottoms of the end wall slots in the deeper slots of said end wall flaps.

4. A container comprising side and end walls, said end walls having inturned upper marginal flaps, said end walls having slots in their upper edges and said inturned flaps having slots in line with said end wall slots but wider and deeper, a reinforcing strip interposed between each end wall and its inturned strip with its upper edge flush with the bottom of the slot in the end wall, cover panels hinged to said side walls, side and end flanges on said cover panels, and tongues carried by said end flanges and secured against the inner faces of said side flanges, said side flanges extending beyond said inturned flaps of said end walls but stopping short of said end walls, said tongues extending through said slots and the edges of said side flanges extending below the bottoms of the end wall slots in the deeper slots of said end wall flaps.

5. A container comprising side and end walls, said end walls having inturned upper marginal flaps connected to said end walls by relatively wide flat joint portions, the lower portions of said flaps being secured to said end walls, said end walls having slots in their upper edges and said inturned flaps having wider slots in line with said end wall slots, cover panels hinged to said side walls, side and end flanges on said cover panels, inwardly and upwardly rebent lining strips on 55 said side flanges, and tongues carried by said end flanges and secured between said side flanges and said lining strips, said side flanges and lining strips extending beyond said inturned flaps of said end walls but stopping short of said end walls, 60 said tongues extending through said slots and said side flanges and lining strips extending into the slots of said end wall flaps.

6. A container comprising side and end walls, said end walls having inturned upper marginal flaps, said end walls having slots in their upper edges and said inturned flaps having slots in line with said end wall slots but wider and deeper, cover panels hinged to said side walls, side and end flanges on said cover panels, inwardly and 70 upwardly rebent lining strips on said side flanges, and tongues carried by said end flanges and secured between said side flanges and said lining strips, said side flanges and lining strips extending beyond said inturned flaps of said end walls but 75

stopping short of said end walls, said tongues extending through said slots and the meeting edges of said side flanges and lining strips extending below the bottoms of the end wall slots in the deeper slots of said end wall flaps.

7. A container comprising side and end walls, said end walls having inturned upper marginal flaps, said end walls having slots in their upper edges and said inturned flaps having slots in line with said end wall slots but wider and deeper, a reinforcing strip interposed between each end wall and its inturned strip, with its upper edge flush with the bottom of the slot in the end wall, cover

panels hinged to said side walls, side and end flanges on said cover panels, inwardly and upwardly rebent lining strips on said side flanges, and tongues carried by said end flanges and secured between said side flanges and said lining strips, said side flanges and lining strips extending beyond said inturned flaps of said end walls but stopping short of said end walls, said tongues extending through said slots and the meeting edges of said side flanges and lining strips extending below the bottoms of the end wall slots in the deeper slots of said end wall flaps. 5 10
